THERMIONIC TUBE FOR DIRECTIONAL RECEPTION

Application filed October 27, 1927, Serial No. 229,045, and in Germany November 5, 1926.

The present invention relates to a convenient construction and arrangement of a thermionic tube in order to make the same adapted to directional reception in combination with two directive antenna systems, and to insure reception as free as possible from disturbance.

In the methods heretofore used for directional reception, a directional characteristic was obtained by suitable antenna combination, which, while showing selective action for a definite direction, exhibited only a limited number of zero points, with the result that, although in weakened condition, energy was received also from most other directions, so that stray waves whenever of sufficient intensity and volume would generally pass into the receiving apparatus from widely different directions.

The object of the present invention is to overcome these disadvantages.

To overcome these disadvantages applicant has provided, according to the present invention, for the object of directional receiving, a thermionic tube which is so built that an action due to the deflection of the cathode-rays is made dependent upon the direction of such deflection. The deflection means of such a thermionic tube are connected with two directional antenna systems. The latter, each of which may have a unilateral directional characteristic, that is, a combination of a high antenna and a loop antenna, may be mounted in the same location, the orientation being so chosen that the directions of maximum signal strength of each antenna system enclose a definite angle in which the station to be received may lie. From the description of the tube and its connection with two directional antennæ, the suitability and the value of the invention for directive reception will be readily understood.

Other objects and advantages will become apparent from the following detailed description when read in connection with the annexed drawing in which;

Fig. 1 is a diagrammatic view of a thermionic tube constructed in accordance with the present invention, and shows the tube con-

nected with a directional radiant energy absorption system,

Fig. 2 is a view showing an end view of the deflection electrodes,

Fig. 3 shows the characteristic curves of the aerials used,

Fig. 4 shows the characteristic curve obtained, while

Fig. 5 shows a modification of the arrangement of Fig. 1.

Referring to the drawing Fig. 1 shows a thermionic tube of the kind here dealt with. Inside the tube, similarly as in a Braun tube, a cathode-ray pencil is produced between cathode C and screen X. The rays are thrown upon a screen X through two pairs of deflection electrodes *aa* and *bb* (see Figs. 1 and 2) which are disposed at right angles to each other. Potential for starting said rays and maintaining said rays is provided by sources 10 and 8 respectively. If alternating current potentials having values A and B and being of the same phase and frequency are connected with the pairs of electrodes *aa* and *bb*, the cathode spot on screen X will make constantly a straight line which forms an angle φ with reference to the direction *aa*. See Fig. 2. φ is a function of the relation between the voltage amplitudes. In the case of symmetrical construction there is

$$\tan \varphi = \frac{B}{A}.$$

The said screen X has a sector-shaped cut-out portion S in which a similarly-shaped metal sheet drained outwardly is arranged. For a certain range of the amplitude relations B:A, as will be seen, the cathode ray pencil will strike and leave the said sector at the rate of the alternating current frequency so that by the leak of the metallic sector S current impulses of like frequency will be caused to flow, and these can be rendered perceptible in a suitable receiver apparatus connected between the source 8 and the sector S. In the presence of other amplitude relations B:A, the said metallic sector will never be struck by the cathode spot, even if the amplitudes are of any large value at all.

If, then, the tube as here described is connected with two uni-directional antenna systems which comprise closed bilateral absorption members L , L_1 , and vertical members V , V_1 , of the same directional characteristics 5 symmetrically coupled through couplings I , I_1 , as shown in Figure 5, so that the potentials of the system V_1 , L_1 , I_1 , come to act upon the pair of plates aa , and the potentials 10 of the second antenna system V , L , I upon the pair bb , the directional antenna structures may be so orientated that, as shown in Fig. 3, their directional characteristics 1 and 2 form an angle with each other. Obviously 15 by suitably orientating the metallic sector in the tube it may be moved to a position at which it is struck by the cathode rays only when the amplitudes of the two potentials fed in are nearly equal. In the presence of 20 absolutely equal amplitudes, in other words, at the point of intersection of the characteristics of Fig. 3, the cathode ray will be deflected by an angle of 45 degrees with reference to the direction of the field of one of 25 the said two pairs of electrodes. We shall assume that the line of symmetry of the collecting sector has an angle of inclination of 45 degrees with reference to the direction of the field of one of the pairs of electrodes so 30 that the sector will be struck by cathode rays under most favorable conditions when they are equal to each other coming from the main direction of reception, in other words, when they are equal from the direction in which, 35 according to the characteristics of Fig. 3, the amplitude of the currents or potentials supplied to the tube from the two antenna structures are equal. To what extent also waves will be received which are at an angle with 40 reference to this main direction of reception, will, for the same antenna systems, depend upon the central angle of the metallic sector.

In the illustration of Fig. 3 it is indicated 45 that the collecting electrode will be struck by cathode rays when the direction differs from the main direction by ± 7 degrees. The angle from which reception is possible will vary according to the shape and orientation of the characteristic curves 1 and 2. 50 The resultant receiving characteristic has a shape as shown in Fig. 4. As can be seen therefrom, the effect which is caused by the employment of such a tube to indicate the oscillations, is sharply limited and the entire 55 system is highly directive. In the case of waves which arrive from a direction opposite to that of reception, the effect is very low as shown in Fig. 4. If the same shall be avoided inside certain limits of intensity, a 60 diaphragm or screening device may be mounted in the neighborhood of the system, or else the receiving sector may be so disposed that its apex will not extend as far as the "point of rest" of the cathode rays so 65 that the sector will be struck by cathode rays

only whenever the deflection exceeds a certain minimum value.

The idea underlying the present invention is capable of various modifications. In the form illustrated in Fig. 1 it is assumed that 70 the collecting electrode has a positive potential, and that it pertains to a circuit comprising an indicator instrument. However, also a screen which, in well-known manner, is caused to luminesce due to the impinging 75 cathode rays may be used as a collecting electrode. This luminous action may be brought by means of a lens 20 to act further upon a photo-electric cell C' as shown in Figure 5, its 80 illumination being indicated by a convenient 85 indicator instrument 14. The screen S may then have the same size, position, and form as sector S , Fig. 1, and will be struck only by such cathode rays as are deflected inside said sector. Moreover, on a larger screen, a corresponding sector can be selected by screening off the light of the other parts so that 90 only the luminous action of the sector is brought to act upon the photo-electric cell. Also a screen may be used which emits secondary electrons whereby an indicator effect 95 may be produced. It will be evident that the arrangement as hereinbefore described in connection with the use of cathode rays may be used with corresponding alterations also 100 when other rays having certain electrical charges, such as canal rays, are employed.

Having now fully described my invention and the operation thereof I claim:

1. A receiving system, comprising means 100 for the generation of a cathode ray pencil, deflection means comprising two pairs of parallel plates disposed at right angles to each other, and an electron collector adjacent the normal path of said ray, the said electron collector comprising a wedge shaped sector the surface of which is at right angles to the direction of the uninfluenced cathode rays, all 105 of the sector being outside the normal path of said rays.

2. A receiving system, comprising means 110 for the generation of a cathode ray pencil, deflection means, a target in the path of said ray, a luminous sector in said target and insulated therefrom, said sector being normally outside of the path of said ray, a photoelectric cell adjacent said tube and in the path 115 of the radiations from said luminous sector when energized, whereby the deflection of the cathode ray pencil by the deflection means causes the ray to fall upon the luminous sector which throws off energy to the photoelectric cell and indicating means associated with said cell.

3. A unidirectional receiving system comprising a cathode ray tube having a ray producing electrode, opposed pairs of deflecting electrodes, and a target comprising a circular disk, a wedge shaped portion of which is 120 electrically separated from the remaining 125

portion, said wedge shaped portion being radially spaced from the normal path of the ray produced by said ray producing electrode, indicating means connected with said wedge shaped portion, and means for applying energy from a unidirectional absorption system to a pair of said deflecting electrodes.

4. A receiving means as recited in claim 3 including means for applying energy from at least two unidirectional absorption systems to opposed pairs of said deflecting electrodes.

5. A unidirectional receiving system comprising a cathode ray tube having a ray producing electrode, opposed pairs of deflecting electrodes, and a target comprising a circular disk, a wedge shaped portion of which is electrically and physically separated from the remaining portion of said disk, the center of said disk being located in the normal path of the ray produced by said electrode, said wedge shaped portion being radially spaced from the normal path of the ray produced by said ray producing electrode, means for applying energy from a different unidirectional absorption system to each opposed pair of said deflecting electrodes whereby the ray produced by said ray producing means is caused to be deflected from its normal path, a photoelectric cell located adjacent said wedge shaped portion and in the path of energy radiated therefrom, and indicating means connected with said photoelectric cell.
